UNITED STATES PATENT OFFICE.

OTTO HEINIGKE, OF NEW Utrecht, NEW YORK, ASSIGNOR TO THE HARTFORD CARPET COMPANY, OF HARTFORD, CONNECTICUT.

DESIGN FOR A CARPET.

SPECIFICATION forming part of Design No. 14,871, dated March 11, 1884.

Application filed January 22, 1884. Term of patent 3½ years.

To all whom it may concern:

Be it known that I, OTTO HEINIGKE, of New Utrecht, in the State of New York, have invented a new and original Design for Carpets, 5 of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

15 The feature of the design is the system of

sprays of lily of the valley and of moss-rose buds between flower groups. These flower groups consist of one or two large open flowers, with clustered leaves and projecting blossom and flower sprays. The intervening sprays 20 are sometimes connected with the flower groups. Some of them bear moss-rose buds and small moss-grown leaves.

I claim—

The design for a carpet, substantially as 25 shown and described.

OTTO HEINIGKE.
